UNITED STATES PATENT OFFICE.

PRESTON B. LEE, OF PHILADELPHIA, PENNSYLVANIA.

GLOVE.

SPECIFICATION forming part of Letters Patent No. 479,285, dated July 19, 1892.

Application filed July 14, 1891. Serial No. 399,507. (No model.)

To all whom it may concern:

Be it known that I, PRESTON B. LEE, a citizen of the United States, residing in the city and county of Philadelphia, and State of Pennsylvania, have invented certain new and useful Improvements in Gloves, of which the following is a specification.

My invention is a glove having bridge-pieces connected at their opposite edges to the lower ends of adjacent finger-stalls, as fully set forth hereinafter, and as illustrated in the accompanying drawings, in which—

Figure 1 is a back view of a glove embodying my improvement. Fig. 2 is a palm view. Fig. 3 is a detached view showing a piece from which a finger-stall is made. Figs. 4 and 5 are palm and back views showing a construction in which the bridge-pieces are parts of the palm-section.

The palm A and the back B may be cut to any suitable shape and formed each in one piece or in sections, and the fingers C may be formed each of a single piece *a*, of the shape shown in Fig. 3, connected with the body portion, as shown in Figs. 1 and 2, or one section 1 of each finger—that is, the back section—may form part of the back piece or pieces, the remaining section 2 of each finger being a separate piece. Whatever may be the construction of these parts, those parts which form the lower ends of the fingers, instead of being connected the end of one finger with the end of the adjacent finger to form a V shape or sharp notch, are connected with an intermediate bridge-piece D, which bridge-piece may be a part of the palm-piece or a part of one of the pieces to constitute the back extending from the palm to the back and serving as a bridge or connection between each pair of fingers. Thus, as shown in Figs. 1 and 2, each bridge-piece D is sewed along the line *x* at each side to the edge of one of the finger-stalls and along the line *y* to the back B and along the line *y'* to the palm A, thereby connecting the adjacent finger-stalls at their lower ends and permitting the same to be readily distended, as is desirable in that class of gloves used for handling reins or by workingmen in operating tools of any kind. It will be seen

that the lines *x x* are practically parallel to 50 each other, so as to form a very strong connection across the notch, and when there are any strains tending to pull the fingers apart, as shown in Fig. 4, there will be less tendency to rip than when the vertical seams converge 55 to a suitable point between the fingers, as in ordinary gloves, and that by thus using the bridge-pieces D, I am enabled to avoid the use of overlying pieces above the ordinary seams at the notches, thus dispensing with the 60 necessity of sewing such seams and avoiding the clumsy construction resulting in such cases.

The bridge pieces or sections D therefore constitute, practically, a part of the glove-body, so that there is but one thickness of material at the notch. The bridge-pieces D may be separate pieces, as shown in Figs. 1 and 2, or they each may be formed by a flap or extension of the palm A, as shown in Figs. 4 70 and 5. The thumb-stall E may be formed and connected with the body in any suitable manner.

Without limiting myself to the precise construction and arrangement of parts shown, 75 I claim—

1. A glove having its adjacent finger-stalls separated at the base and the openings thus formed closed by bridge-pieces completely spanning the opening from front to rear and 80 stitched at their side edges to the lower edges of the adjacent sides of the finger-stalls, substantially as described.

2. A glove having the adjacent finger-stalls separated at the base and the openings so 85 formed closed by bridge-pieces D, each formed by an extension of the palm extending from front to back between two of the finger-stalls and each stitched at its side edges to the lower edges of the adjacent sides of the finger-stalls, 90 substantially as set forth.

In testimony whereof I have signed my name to this specification in the presence of two subscribing witnesses.

PRESTON B. LEE.
